UNITED STATES PATENT OFFICE.

MARY A. BREADHEFT, OF INDIANAPOLIS, INDIANA, EXECUTRIX OF
SAMUEL MARTIN GANT, DECEASED, ASSIGNOR TO SARA O. WILSON.

PARTY-LINE TELEPHONE SYSTEM.

No. 799,887.

Specification of Letters Patent.

Patented Sept. 19, 1905.

Application filed February 24, 1903. Renewed February 16, 1905. Serial No. 245,875.

To all whom it may concern:

Be it known that I, MARY A. BREADHEFT, executrix, a citizen of the United States, residing at Indianapolis, in the county of Marion, State of Indiana, am in possession of an invention in certain new and useful Improvements in Party-Line Telephone Systems, invented by SAMUEL MARTIN GANT, deceased, of which the following is a specification.

10 In the present system of telephonic communication a continuous current is used for the talking-circuit and an alternating current is used for the ringing-circuit.

The object of the present invention is to 15 provide a mechanism by which these two currents may be utilized and controlled by central to cut out all but a particular one of a number of party-line phones at any particular time in order that, so far as bell-ringing, 20 and secrecy of conversation is concerned, the party-line service becomes equal to an individual-line service, the arrangement being such that no party other than the one predetermined by central may cut in.

25 The accompanying drawings illustrate the invention.

Figure 1 is a diagrammatic illustration of the apparatus for a two-party line, the parts being shown in normal position. Figs. 2, 3, 30 4, 5, 6, 7, and 8 indicate the successive steps in the apparatus preliminary to cutting out phone Y. Fig. 9 is a similar view showing the parts in condition for ringing the bell of phone X and for permitting conversation 35 thereover without permitting conversation over phone Y. Figs. 10, 11, 12, 13, 14, 15, and 16 show subsequent steps preliminary to cutting out phone X and cutting in phone Y. Fig. 17 is a similar view showing the parts in 40 position for use of phone Y. Fig. 18 is a diagram of the wiring for a three-phone group, showing the method of adding additional instruments to the main line.

The subcentral apparatus is composed of a 45 plurality of relays or circuit-changers arranged in two sets, one set to be affected by the alternating current and those of the other set to be affected by the direct current, or, stated more broadly, the circuit-changers of 50 one set to be affected by a current through one circuit while the circuit-changers of the other set are to be affected by a current through another circuit. If desired, the circuit-changers to be affected by the alternating current may

consist of a suitable coil, within which is pivoted an armature which forms the core for a coil connected either in series or in parallel with the surrounding coil, the said arm carrying a suitable finger to operate the terminals and being yieldingly held in one position by a suitable spring. The changers to be affected by direct current may be similar to the other changers except that a polarized armature may be used.

With these units the apparatus at subcentral for a two-party line is composed of wound circuit-changers A, B, C, D, E, K, and M, and unwound or polarized circuit-changers F, G, H, I, J, and L.

The main-line wires of the system are indicated at 33 and 34, line 33 serving as a leading-in wire for both circuits and connected by wire 35 with binding-post 36 of the subcentral apparatus. Binding-post 37 of this apparatus is grounded through a switch e, and 70 a binding-post 38 is connected through a switch a and wire 198 with the wire 34. Connected with binding-post 36 is a bus-bar 39. Connected with binding-post 38 is a bus-bar 40, a magnet-coil N forming part thereof, 80 and connected to binding-post 37 is a bus-bar 41. Bus-bars 42 and 43 are also provided for a purpose which will appear. The coil of changer A is connected to one side of a condenser 44 by a wire 45, and the opposite side 85 of said condenser is connected by a wire 46 to bus-bar 39, while a wire 47 connects wire 45 and bus-bar 42.

Changer A is provided with a spring-terminal 48, adapted to be engaged by the insulating-head of the armature thereof and thrown into engagement with a stationary terminal 49.

Changer B is provided with a pair of companion spring-terminals 50 and 51 and coöperating stationary terminals 52 and 53, respectively. Changer B is also provided with a third spring-terminal 54, coöperating with a stationary terminal 55, the arrangement being such that when the insulating-head of the armature is in engagement with the companion terminals 50 and 51 it will not engage the terminal 54, and vice versa. The normal position of the armature of changer B is such as to hold terminals 50 and 51 into engagement with their coöperating terminals 52 and 53, 100 respectively.

Changer C is provided with a pair of companion terminals 56 and 57, which coöperate

with stationary terminals 58 and 59, respectively, the normal position of the armature of changer C being out of engagement with the spring-terminals 56 and 57.

5 Changer D is provided with a pair of companion terminals 60 and 61, which coöperate with stationary terminals 62 and 63, and is also provided with an opposed spring-terminal 64, coöperating with a stationary terminal 65, 10 the normal position of the armature of changer D being such as to throw terminal 64 into contact with terminal 65.

Changer E is provided with a spring-terminal 66, coöperating with a stationary terminal 15 67, the said spring-terminal being normally engaged by the armature, and is also provided with a spring 68, opposed to spring-terminal 66, and said spring-terminal 68 coöperating with a stationary terminal 69.

20 Changer F is provided with a spring-terminal 70, normally engaged by the armature and held in contact with a stationary terminal 71. Changer F is also provided with a pair of companion spring-terminals 72 and 73, which 25 coöperate with stationary terminals 74 and 75, respectively.

Changer G is provided with a spring-terminal 76, normally held in contact with a stationary terminal 77, and is also provided with a 30 pair of companion terminals 78 and 79, normally out of contact with stationary terminals 80 and 81, respectively.

Changer H is provided with a terminal 82, normally held in contact with stationary terminal 83, and is also provided with a pair 35 of companion spring-terminals 84 and 85, normally out of contact with stationary terminals 86 and 87, respectively.

Changer I is provided with a single spring-terminal 88, normally out of contact with stationary terminal 89.

Changer J is provided with a pair of companion spring-terminals 90 and 91, normally out of contact with stationary terminals 92 45 and 93, respectively.

Changer K is provided with a spring-terminal 94, normally held by the armature in contact with a stationary terminal 95, and is also provided with a pair of companion terminals 96 and 97, normally out of contact with stationary terminals 98 and 99, respectively.

Changer L is provided with a pair of companion terminals 100 and 101, normally out of contact with stationary terminals 102 and 55 103, respectively.

Changer M is provided with a spring-terminal 104, normally held in contact with stationary terminal 105, and is also provided with a pair of companion spring-terminals 106 and 60 107, normally out of contact with stationary terminals 108 and 109, respectively.

Located in the bus-bar 40, so as to serve as a shunt for alternating currents around the coil of magnet N, is a condenser 110. Magnet 65 N has an armature 111, which connects and

serves to operate spring-terminals 112 and 113, one of such terminals being provided for each phone of the party and coöperating with stationary terminals 114 and 115, respectively.

Mounted in phone X is a polarized changer 70 O, which is provided with a spring-terminal 116, normally held by the armature in engagement with a stationary terminal 117, and is also provided with a pair of spring-terminals 118 and 119, normally out of engagement with stationary terminals 120 and 121. Similarly, phone Y is provided with a polarized changer 75 P, provided with a spring-terminal 122', normally in contact with stationary terminal 122, and with a pair of companion terminals 123 80 and 124, normally out of contact with stationary terminals 125 and 126.

As has been previously stated, one end of the coil of changer A is connected by wire 45 with one side of the condenser 44. The opposite end of the armature-coil of A is connected by a wire 127 with spring-terminal 51. Terminal 52 is connected by a wire 132 with bus-bar 40. Terminal 53 is connected by wire 128 to bus-bar 41. Terminal 55 is connected by a wire 129 with one end of the coil of B, while wire 130 connects the opposite end of the armature-coil of B with bus-bar 43. Terminal 55 is also connected by wire 131 with terminal 75. Terminal 56 is connected by wire 133 with bus-bar 43 and is also connected by a wire 134 with terminal 79. Terminals 58 and 81 are connected with each other and with one end of the coil of C by wire 135. Terminal 57 is connected by wire 136 with terminal 91 and also with one end of the coil of J. Terminals 59 and 84 are connected by a wire 137, said wire also connecting with one end of the coil of H, the opposite end of said coil being connected by wire 138 with bus-bar 40. The opposite end of the armature-coil of C is connected by wire 139 with terminal 64, and terminal 65 is connected by wire 140 with bus-bar 41. Terminals 62 and 87 are connected together and to one end of the armature-coil of D by a wire 141, while the opposite end of the coil of D is connected by a wire 142 with terminal 66. Terminal 67 is connected by a wire 143 with one end of the coil of E and also with bus-bar 41. The opposite end of the armature-coil of E is connected by a wire 144 with terminals 69 and 89. Terminals 68 and 88 are connected together and to bus-bar 43 by a wire 145. Terminal 63 is connected by a wire 146 with one end of the coil of I, while the opposite end of said coil is connected by wire 147 with bus-bar 40. Terminals 61 and 101 are connected together and to one end of the coil of L by wire 148. Terminals 86 and 82 are connected together and to bus-bar 39 by a wire 149. Terminal 83 is connected by a wire 150 to that end of the coil of L opposite wire 148. Terminals 85 and 60 are connected by wire 1149 to each other and to bus-bar 43. 130

100 Terminals 58 and 81 are connected with each other and with one end of the coil of C by wire 135. Terminal 57 is connected by wire 136 with terminal 91 and also with one end of the coil of J. Terminals 59 and 84 are connected by a wire 137, said wire also connecting with one end of the coil of H, the opposite end of said coil being connected by wire 138 with bus-bar 40. The opposite end of the armature-coil of C is connected by wire 139 with terminal 64, and terminal 65 is connected by wire 140 with bus-bar 41. Terminals 62 and 87 are connected together and to one end of the armature-coil of D by a wire 141, while the opposite end of the coil of D is connected by a wire 142 with terminal 66. Terminal 67 is connected by a wire 143 with one end of the coil of E and also with bus-bar 41. The opposite end of the armature-coil of E is connected by a wire 144 with terminals 69 and 89. Terminals 68 and 88 are connected together and to bus-bar 43 by a wire 145. Terminal 63 is connected by a wire 146 with one end of the coil of I, while the opposite end of said coil is connected by wire 147 with bus-bar 40. Terminals 61 and 101 are connected together and to one end of the coil of L by wire 148. Terminals 86 and 82 are connected together and to bus-bar 39 by a wire 149. Terminal 83 is connected by a wire 150 to that end of the coil of L opposite wire 148. Terminals 85 and 60 are connected by wire 1149 to each other and to bus-bar 43. 130

Terminal 80 is connected by wire 1150 with bus-bar 39. Terminal 77 is connected by wire 151 with that end of the coil of J opposite wire 136. Terminal 76 is connected to bus-bar 39 by wire 152. Terminals 78 and 74 are connected together and to one end of the coil of G by wire 153, the opposite end of said coil being connected by a wire 154 with bus-bar 40. Terminal 72 is connected by a wire 155 with bus-bar 39 and with one end of the coil of F, the opposite end of said coil being connected by a wire 156 with terminal 48. Terminals 50 and 49 are connected by a wire 157. Terminal 73 is connected by wire 158 with bus-bar 42. Terminal 70 is connected by a wire 159 with the spring-terminals 112 and 113 and also with terminals 95 and 105. Terminal 71 is connected to bus-bar 39 by wire 160. Terminal 93 is connected by a wire 161 with bus-bar 40, and terminals 90 and 97 are connected together and to bus-bar 42 by a wire 162. Terminals 92 and 99 are connected together and to one end of the armature-coil of K by wire 163, the opposite end of the coil of K being connected by wire 164 with bus-bar 41. Terminal 96 is connected by wire 165 with bus-bar 39, and terminal 98 is connected by wire 166 with binding-post 167. Terminal 103 is connected by a wire 168 with bus-bar 40, and terminals 100 and 107 are connected together and to bus-bar 42 by wire 169. Terminals 102 and 109 are connected together and to one end of the armature-coil of M by wire 170, the opposite end of the coil of M being connected by wire 171 to bus-bar 41. Terminal 106 is connected by wire 172 with bus-bar 39, and terminal 108 is connected by wire 173 with binding-post 174.

The wire 175 leads from bus-bar 40 to binding-post 176. Leading from terminal 104 is a wire 177, which leads to terminal 126 of phone Y, and leading from terminal 94 is a wire 178, which leads to terminal 121 of phone X. Terminal 114 is connected by wire 179 with terminal 119 of phone X and one end of coil of O, the opposite end of said coil being connected by a wire 180 with terminals 118 and 181. Terminal 181 is adapted to be normally contacted by spring-terminal 182, normally held by the receiver-hook 183 of phone X. Leading from line-wire 34 is wire 184, which is split and connects with terminals 125 120, spring-terminal 182 of phone X, and a similar spring-terminal 185 of phone Y, said spring-terminal being normally held by receiver-hook 186 in contact with terminal 187. Terminal 187 is connected by a wire 188 with spring-terminal 123 of phone Y, and with one end of the coil of P, the opposite end of coil of P being connected by wire 189 with terminals 115 and terminal 124. Leading from binding-post 167 is a wire 190, which wire leads to one of the terminals of the bell of phone X. Leading from the binding-post 176 is a wire 191, which is split and leads to the bells of both phones. Leading from binding-post 174 is a wire 192, which leads to the other terminal of the bell of phone Y. Leading from terminal 117 is a wire 292, which forms part of the receiver-circuit of phone X, and leading from terminal 116 is a wire 193, which connects with line-wire 33. Similarly in phone Y wire 194 connects terminal 122 with the receiver-circuit, and wire 195 connects spring-terminal 122' with line-wire 33. The opposite side of the receiver-circuit of the phone Y is formed by wire 196, connected with line-wire 34, and similarly in phone X the opposite side of the receiver-circuit is a wire 197, connected with line-wire 34. Post 38 is connected by a wire 198 with line-wire 34 through switch *a*, and in front of switch *a* wire 199 leads through a switch *b* to the grounded side of the alternating generator 200. The opposite side of said generator connects by wire 201 with line-wire 33, and a battery 202 is connected to the line-wires 33 and 34.

The normal position of the parts is that shown in Fig. 1. Suppose now that a call has been sent in for connection with phone X. The operator first closes switch *c*, and immediately a circuit is established from generator 200 through wire 201, line-wire 33, wire 35, bus-bar 39, wire 46, condenser 44, wire 45, coil of A, wire 127, terminals 51 and 53, wire 128, bus-bar 41, binding-post 37, and through switch *c* to the ground, whereupon the armature of A is thrown to the left, as shown in Fig. 2, and serves to force spring-terminal 48 against terminal 49, and thus close the circuit, which begins with wire 35 and passes through bus-bar 39, wire 155, coil of F, terminals 48 and 49, 50 and 52, bus-bar 40, through coil N and switch *a* to the opposite line-wire 34. Switch *a* is then closed, Fig. 3, whereupon the armature of F throws to the right, and coil N draws armature 111 so as to bring terminals 112 and 113 down into contact with terminals 114 and 115, respectively. This action of coil N would close the circuits through the coils O and P; but by the time coil N has drawn the terminals down to contacting position the armature of F has moved so as to break the cut-out circuit at the terminals 70 and 71, and there is therefore no action in the phones X and Y. When the armature of F moves to the right, it forces terminals 72 and 73 into contact with terminals 74 and 75, respectively. Through terminals 72 and 74 a circuit is closed from bus-bar 39 through wire 155, terminals 72 and 74, and wire 153, through coil of G, and wire 154 to bus-bar 40. At the same time the closing of terminals 73 and 75 closes part of a circuit through coils of B and C. As soon as coil of G is energized the armature thereof moves to the right, Fig. 4, and through terminals 78 and 80 closes a new circuit from bus-bar 39, through wire 1150, terminals 80 78, wire 153, 130

through its own coil and wire 154 to bus-bar 40, so as to be thus held over by reason of its new position, and also closes terminals 79 and 81, which completes the following circuit: Beginning with bus-bar 39 and running through wire 46, condenser 44, wire 45, wire 47, bus-bar 42, wire 158, terminals 73 75, wire 131, wire 129, coil of B, wire 130, bus-bar 43, wire 133, wire 134, terminals 79 and 81, wire 135, coil of C, wire 139, terminals 64 and 65, wire 140 to bus-bar 41. Thereupon armature of B swings to the right and armature C swings to the left, as shown in Fig. 5, and the following actions take place: The movement of armature B breaks the circuit through coil of A (at terminals 51 53) and the circuit through coil of F at terminals 50 52, so that said coils move to their normal positions, as shown in Fig. 5, and it also closes at terminals 54 and 55 a circuit through its own coil and coil of C and terminals 64 and 65, so as to be held over by its own new position.

The movement of the armature F, Fig. 5, to its normal position closes the cut-out circuit at terminals 70 and 71, so that, beginning with bus-bar 39, we have the following circuits: through wire 160, terminals 71 70, wire 159, terminals 112 and 113 in parallel, first, through terminal 114, wire 179, coil of O, wire 180, terminals 181 182, wire 184 to the opposite line-wire 34, (bus-bar 39 being connected by wire 35 with line-wire 33,) and, second, through terminal 115, wire 189, coil of P, wire 188, terminals 187 and 185, and wire 184 to line-wire 34, so that the armatures of O and P are simultaneously thrown to the right and the receiving-circuits of both phones are broken at terminals 116 117 and 122' 122. The movement of armature of F to the left also breaks the coil of B circuit at terminals 73 75; but coil of B, as has already been explained, lies in a new circuit at terminals 54 55 by reason of its movement to the right, as shown in Fig. 5, and is not affected by the change of position of armature of F. The change of armature of F also breaks a circuit through coil of G; but coil of G lies in a new circuit through terminals 78 and 80 and it is not affected.

The movement of armature of C to the left establishes a new circuit through its own coil by reason of the contact of terminals 56 and 58, and it also closes part of a circuit through coils of H and J at terminals 57 59, but only part, so that these coils of H and J do not yet become energized. The movement of armature of B to the right breaks (at terminals 51 and 53) the alternating circuit through the coil of A, and the armature of A therefore returns to normal position, and this return causes a second break at terminals 48 49 in the circuit through coil of F. When the parts have reached this position, the operator breaks the direct-current circuit at switch *a*, Fig. 6, and thereupon magnet N is deenergized and

terminals 112 and 113 separate from terminals 114 and 115, respectively, and the armatures of O and P return to normal, reestablishing the receiver-circuits of the two phones. At the same time the coil of G is deenergized and the armature thereof returns to normal, thus breaking the original circuit through coil of C at terminals 79 and 81; but coil of C is not affected by reason of establishment in the new position of its armature of a circuit through terminals 56 58. The return of G to normal completes the circuit at terminals 76 and 77 through the coils of J and H. Thereupon the operator closes switch *a*, and in Fig. 7 are shown the following changes of position resulting therefrom: Magnet N draws terminals 112 and 113 down so as to close the cut-out circuits of both phones, and the armatures of O and P therefore again move to the right, thus breaking the receiver-circuits of both phones. Simultaneously armature of J moves to the right, closing its own coil through 91 93, and closing the coil of K through terminals 90 92. Armature of H also moves to the right, closing its own coil through terminals 84 and 86 and closing the coil of D through terminals 85 and 87. Thereupon, Fig. 8, D moves to the left by reason of the action of armature of H, and this breaks the circuit through coil of C at terminals 64 65 whereupon the armature of C moves to normal. The movement of armature of D to the left also closes its own coil through terminals 60 62. The movement of armature of C to normal breaks the circuit at terminals 57 59 through coil of J, and armature of J therefore moves to normal. As soon as the armature of J has been moved to the right by reason of the establishment of a circuit through its coil by the movement of the armature of G a circuit is established through terminals 90 and 91 through the coil of K, and the armature of K is therefore moved to the right before the circuit of coil of J is broken by reason of the action of the armature of C and the movement of the armature of K to the right resulting first in a breaking of the circuit of coil of O at the point 94 95, so that armature of O returns to normal position and closes the receiver-circuit at 116 117. Thereafter upon the completion of movement of armature of K a new circuit is established through its own coil by reason of the contact of terminals 97 and 99, and at the same time a ringing-circuit is established by reason of the contact of terminals 96 and 98. Beginning with line-wire 33 and running through wire 35, bus-bar 39, wire 165, terminals 96 98, wire 166, wire 190, the bell-coil (not shown) of phone X, wire 191, wire 175, bus-bar 40, (through condenser 110 as a by-pass around the coil of magnet N,) and thence through wire 198 and wire 199, through switch *b* to generator 200 and wire 201 to the line-wire 33, so that the operator by closing switch *b* may

cause the bell of phone X to ring, while the bell of phone Y will remain silent owing to the fact that its ringing-circuit is broken at the point between terminals 106 and 108 of 5 the circuit-changer M. Switch *a* is then opened, armature of H returned to normal, and the position of parts at this time therefore is that shown in Fig. 9, and the parts are in position to permit conversation over 10 phone X.

If instead of a connection with phone X a connection with phone Y is desired, the operator at central instead of closing switch *b* will again close switch *a*, Fig. 10, whereupon 15 magnet N brings terminals 112 113 down so as to close the cut-out circuit and throw armature of O to the right, the armature of P being already to the right. At the same time there is a complete circuit through wire 20 149, terminals 82 83, wire 150, coil of L, wire 148, terminals 61 63, wire 146, coil of I, and wire 147, so that the armatures of I and L will throw simultaneously to the right, Fig. 10. The movement of armature of I brings 25 terminal 88 against terminal 89, and thus closes a circuit through coil of E, whereupon the armature of E moves to the left, Fig. 11, and breaks the circuit through coil of D at 66 67 and also closes a new circuit through 30 its own coil at 68 69, so that it holds itself over. When D moves to the right (its normal position) by reason of the break in the circuit of its coil caused by the movement of the armature of E, it breaks the 35 circuit through coil of I at 61 63, whereupon I returns to normal position, separating terminals 88 89; but the armature E holds over by reason of the contact between 68 69. The movement of L to the right simultaneously 40 with the movement of armature of I, caused by the closing of switch *a*, closes its own coil 101 103 and also closes a circuit through coil of M at 100 102, whereupon armature of M moves to the right and breaks the receiver-circuit of phone Y at 104 105. This movement of armature of M closes a circuit through 45 its own coil at 107 109 and also closes the ringing-circuit of phone Y at 106 108. With the apparatus in this position, Fig. 11, it would 50 be possible to ring both bells; but the receiver-circuit in each phone is cut. Therefore it is necessary to return armature of K to its normal position, and in order to do this the operator breaks switch *c*, whereupon the armatures of B, E, K, and M return to normal positions, Fig. 12, and the apparatus is in normal position, with the exception that armature of L is thrown to the right, and the armatures of O and P of the two phones are also thrown 55 to the right, so that the two receiver-circuits are cut. The operator then closes switch *c*, whereupon the armature of M again moves to the right, so as to break the circuit of coil of P at 104 105, permitting the armature of P to 60 return to normal position and close the re-

ceiver-circuit of phone Y at 121 122, at the same time closing a circuit through its own coil at 107 109 and closing the ringing-circuit of phone Y at 106 108, Fig. 13. The closing of switch *c* also causes movement of armature of A, and this causes the same sequence of operation which it caused in the initial movements—that is, in Fig. 14 armature of F moves to the right, as in Fig. 3, and breaks the cut-out circuit at 70 71, so that the 75

armatures of O and P return to normal position. The movement of F to the right causes armature of G to move to the right, Fig. 15, as in Fig. 4. This movement of G, as illustrated and described in Fig. 5, causes armature of B to move to the right, Fig. 16, armature of C to move to the left, armature of F to move to the left, as in Fig. 5, and by reason of the reestablishment of the cut-out circuit at 70 71 armature of O moves to the right, 80 so as to break the receiver-circuit of phone X at 116 117, the circuit through the coil of O being completed by reason of the normal position of the armature of K at 94 95. The circuit through coil of P, however, is not completed, owing to the fact that the armature of M lies out of normal position, so as to break the coil-circuit at 104 105. The operator then breaks switch *a*, whereupon the armatures of G and L return to normal, and by closing 85 switch *b* the bell of phone Y may be rung and conversation may be permitted over phone Y.

The apparatus may be expanded for party-lines having more than two parties by adding 90 additional circuit-changing elements wound 100 and polarized.

The method of expanding the apparatus described is clearly shown in Fig. 18, where an additional instrument Z has been added. In this case a polarized changer Q and a wound-armature changer R are added, these being duplicates of the changers L and M, respectively. The changer I is then provided with a pair of oppositely-arranged spring-terminals 210 and 211, terminal 210 being arranged 105 on the same side as terminal 88 and being connected with the coil of changer I. Spring-terminal 211 is connected to the main bus-bar 39. Coöperating with spring-terminal 210 is a stationary terminal 212, which is connected to spring-terminal 211, and coöperating with spring-terminal 211 is a stationary terminal 213, which is connected to the coil 110 of changer Q. The terminals, both spring and stationary, of the changers Q and R are connected to the bus-bars and to the instrument Z in the same way as are the changers L and M, respectively. There is also provided another terminal 214, which coöperates 115 with the spring-terminal 215, similar to the terminals 115 and 113, respectively, the terminal 215 being connected to the terminals 112 and 113 and the terminal 214 being connected to the spring-terminal 216 of the phone Z, which terminal corresponds to terminal 120 125 130

124 or 119 of the phones Y and X, respectively, this spring-terminal being also connected to the coil of the changer in phone Z.

In order to connect phone Z, the operator 5 would proceed, as has already been described, up to the point of connecting phone Y. Then instead of closing switch *b* to ring phone Y would close switch *a*, whereupon the circuit through the coils of J and H would be completed, (through terminals controlled by G and C,) and J and H would therefore throw to the right, Fig. 17. Keeping Fig. 17 in mind, the movement of J will close the coil of K, and it will move to the right, while the 10 movement of H closes coil D, and it moves to the left. The movement of D opens coil C, and C thereupon drops to normal. The operator would then open switch *a*, whereupon J and H drop to the left. Switch *a* is then closed 15 and L and I move to the right, the movement of I causing a movement of E to the left, so that E breaks the coil of D, and D moves to the right. The operator then opens switch *a*, and I and L move to the left. The movement of I to the 20 left brings terminals 211 and 213, Fig. 18, together, so as to close this break in the coil of Q. Thereupon switch *a* is again closed, resulting in a movement of Q to the right. The operator then opens switch *c*, whereupon 25 M, K, E, and B return to normal. Switch *c* is then closed, and R moves to the right, thus cutting in phone Z.

It will be seen that the expansion of the system requires no further apparatus at central, the only difference being the additional elements, which may be termed the "subcentral" and which are connected to central by the main circuits.

If another instrument is to be added, a new 30 element corresponding to the element E would be placed in the right-hand row and connected in the same manner as the changer E. Another element corresponding to the element I, as shown in Fig. 1, would also be 35 added and similarly connected, and two elements corresponding to the new elements Q and R would also be added and connected, as are these elements. The number of instruments to be added is unlimited, four additional elements being added for each new instrument. Fig. 18 shows more clearly the 40 manner of wiring, the selector being placed in the near neighborhood of the instruments, which are to be arranged in a single group, and the three main-line wires running from 45 central to the selector.

It will be readily understood that ratchet mechanism may be provided to automatically close and open the several switches *a*, *c*, and 50 *b*, if desired.

It will be noticed that when proper connections have been made by central with any one of the party-phones the bell of that phone is the only one which rings, the bells of the 55 other phones being silent and the silent phones

being absolutely cut out from the system, and that this is entirely independent of the number of phones in the party. If, however, a party desires to talk to another party on the same line, the mere lifting of the receiver from 70 its hook breaks the circuit in that phone—as, for instance, at 185 187 in phone Y—so that central cannot cut out this phone. The apparatus may be placed at any convenient point other than central—as, for instance, in a building, but controlled from central—if desired. 75 With this arrangement it is true any party may by lifting his receiver cut his own phone in so as to overhear a conversation; but the cutting in must be done prior to the operation of the device at central and such operation will of course notify central. 80

It will be readily understood that the cut-out armature of each phone may carry or operate a "busy" signal to indicate the condition of the phone, if desired. 85

I claim as the invention of SAMUEL MARTIN GANT—

1. In a party-line telephone system, the combination, with a pair of main-line circuits 90 and energizers therefor, of a plurality of telephones connected to both circuits, cut-out means for each telephone, two sets of circuit-changers, connections between the several circuit-changers and between the circuit-changers and the cut-out means of the telephones, and means for energizing and deenergizing the several circuit-changers. 95

2. In a party-line telephone system, the combination, with a pair of main-line circuits, 100 a direct-current generator connected to one of said circuits, an alternating-current generator connected to the other of said circuits, a plurality of telephones connected to both circuits, cut-out means for each telephone, a 105 plurality of circuit-changers affected by direct current, a plurality of circuit-changers affected in one direction by alternating current, connections between the terminals of the several circuit-changers, and connections 110 between each telephone cut-out and a circuit-changer affected by alternating current.

3. In a party-line telephone system, the combination, with a pair of main-line circuits, 115 a plurality of telephones connected to said circuits, a direct-current generator connected to one of said circuits, an alternating-current generator connected to the other of said circuits, a plurality of circuit-changers uniformly affected by the alternating current, connections 120 between said circuit-changers and the alternating-current circuit, a plurality of circuit-changers affected by the direct current, connections between said circuit-changers and the direct-current circuit, separable connections 125 between the several circuit-changers, a receiver cut-out in each telephone, a circuit-breaker for each telephone forming part of one of the circuit-changers affected by alternating current, and a ringing-circuit for each 130

telephone extending to and separable by the said circuit-changer.

4. In a party-line telephone system, the combination, with the main line 33 34, the direct-current generator and the alternating-current generator, of the circuit-changers, A, B, C, D, E, F, G, H, I, J, K, L, and M of the subcentral apparatus, circuit-changers O and P, magnet N, armature 111, and intermediate connections between the several parts, as described and for the purpose set forth.

5. In a party-line telephone system, the combination, with two main circuits carrying currents of different characteristics, of a successive selector consisting of a plurality of circuit-changers part of which are affected by one current and part by the other, a plurality of telephones, connections between successive telephones and successive portions of the selector, and means operable from central for causing the two currents to successively operate the several changers and thereby connect a desired telephone to the exclusion of others.

25 6. In a party-line telephone system, a selector therefor consisting of a series of circuit-changers affected by a current of one characteristic, another series of circuit-changers affected by a current of another characteristic, intermediate electrical connections between the several terminals of the two series, and terminals forming part of the changers of one series which may be connected with individual telephones, for the purpose set forth.

35 7. In a party-line telephone system, the combination, with two main circuits carrying currents of different characteristics, of a subcentral apparatus consisting of two sets

of circuit-changers the changers of one set being affected by one current and the changers of the other set being affected by the other current, intermediate connections between the changers of the two sets, a plurality of telephones, connections between successive telephones and successive portions of the subcentral apparatus, and means for opening and closing the main circuits at central whereby the circuit-changers of the subcentral apparatus may be successively affected and the several telephones connected successively with the main-line circuit.

8. In a party-line telephone system, the combination, with two main circuits, of a subcentral apparatus consisting of two sets of circuit-changers the changers of one set being affected by current in one circuit and the changers of the other set being affected by current in the other circuit, intermediate connections between the changers of the two sets, a plurality of telephones, connections between successive telephones and successive portions of the subcentral apparatus, and means for opening and closing the main circuits at central whereby the circuit-changers of the subcentral apparatus may be successively affected and the several telephones connected successively with the main-line circuit.

In witness whereof I have hereunto set my hand and seal, at Indianapolis, Indiana, this 20th day of February, A. D. 1903.

MARY A. BREADHEFT, [L. S.]
Executrix of the estate of Samuel Martin Gant, deceased.
